(57) **CLAIM**

The ornamental design for a golf bag, as shown and described.

DESCRIPTION

FIG. 1 is a front elevation view of a golf bag;

FIG. 2 is a rear elevation view of the golf bag;

FIG. 3 is a right side elevation view of the golf bag;

FIG. 4 is a left side elevation view of the golf bag; and,

FIG. 5 is a top plan view of the golf bag.

The bottom of the golf bag is flat and devoid of surface ornamentation. The broken lines are for illustration purposes only and form no part of the claimed design. The black portions of the golf bag indicate color contrast with the non-black portions of the golf bag. The particular color black is not claimed.
